UNITED STATES PATENT OFFICE.

SAMUEL SINKLER, OF CHICAGO, ILLINOIS, ASSIGNOR OF ONE-HALF TO FREDERICK ITZKOWITZ, OF NEW YORK, N. Y.

ADJUSTABLE MIRROR-SUPPORT.

1,182,110.

Specification of Letters Patent.

Patented May 9, 1916.

Application filed November 2, 1914. Serial No. 869,852.

To all whom it may concern:

Be it known that I, SAMUEL SINKLER, a citizen of the United States, residing at Chicago, in the county of Cook and State of Illinois, have invented certain new and useful Improvements in Adjustable Mirror-Supports, of which the following is a description, reference being had to the accompanying drawings, forming a part of this specification, in which corresponding letters of reference in the different figures indicate like parts.

The object of my invention is to provide an adjustable device for the support and universal manipulation of a plurality of mirrors for toilet purposes and for the use of milliners, doctors and other specialists requiring an indefinite variety of mirror adjustments.

20 To these ends, my invention consists in the combination of elements hereinafter more particularly described and definitely pointed out in the claims.

In the drawings, Figure 1 is a rear elevation of a device, embodying the features of my invention. Fig. 2 is a view of one of the mirrors as it would appear in its supporting frame. Fig. 3 is a vertical section taken upon the line 3, Fig. 4. Fig. 4 is a plan view of the main extensible supporting part. Fig. 5 is a face of the clip which supports the expandible mirror-holding arms, and Fig. 6 is a section taken upon the line 6—6, Fig. 2, viewed in the direction of the arrow there shown.

Referring to the drawings, 1 indicates a base member which may be placed upon a table or other support or if desired, secured as a bracket to a wall or upright by means 40 of a central screw or bolt. Pivoted to the base 1, at a plurality of equi-distant points 2, preferably three in number, which are equi-distant from a common center, are pairs of parallel bars 3, which are in turn jointedly connected at 4, to like bars 5, the outer ends of which are jointedly attached by means of rivets 6, to lugs 7, formed upon body parts 8, attached by means of rivets 9, to a tubular member or ring 10.

50 Pivotedly secured to the upper part of the tube 10 at diametrically opposite points 11, 11, are lugs 12, 12, which are integral with a connecting plate 13. This plate in turn is centrally pivoted at 14, to a flat plate 15, having slots 16, 16 therein arranged in a line-

ment with each other and equally distant from the pivotal point 14. Extending loosely through the slots 16, so as to be moved therein, are rivets 17, 17, which are passed through bores in, and serve to connect and form 60 pivots for counterpart lazy-tongs members 18, 19, and 20, 21, respectively. Washers 22, Figs. 3 and 4, are interposed between the plate 15 and said lazy-tongs members.

Connected with the lazy-tongs members 65 18, 19, 20 and 21, by means of rivets in a well known way, so as to extend in opposite directions from the central pivoted supporting plate 15, are similar lazy-tongs members, generally designated by 23 in Fig. 1. 70 The rivets 24 and 25, in the end members 26 and 27, respectively, are passed through slots 28, 29 in bracket members 30, also shown in Fig. 2, having lugs 31, 31, jointedly connected at 32 to counterpart lugs 33, 75 33 upon oppositely extended curved arms 34, 34, which are in turn pivotally connected at diametrically opposite points to the frame 36, of a mirror generally designated by 37,— 80 one mirror being at the end of each lazy-tongs extension. It will be noted that the backs of the mirrors are shown in Fig. 1, and the front in Fig. 2. In Fig. 6 is shown a cross section of the circular frame and the manner in which the glass and backing are 85 secured therein.

Each of the several joints of the main support as well as those of the lazy-tongs extension, are adjusted by tightening the rivets so as to produce sufficient friction 90 therein to maintain the parts in any predetermined position in which they may be placed. For example, the height of the supporting ring 8, which with its connections forms a universal joint for the extensible 95 mirror supporting arms, may be varied by manually lifting or depressing the main supports. For the purpose of extending or retracting said arms or lazy-tongs extensions. I provide arms 38, 39, Fig. 1, the drawing together or separation of which may enable said parts to be extended or retracted to any desired extent, or swung upon the universal joint to any position, horizontal, vertical or otherwise to suit the 100 requirements of the user. Should the part 1 be placed upon a table, it is obvious that the adjustable parts connected therewith would extend upwardly and their adjustment would merely serve to raise or lower 110

the swivel joint connection. On the other hand should the part 1 be attached to a wall, the manipulation of the bars 3 and 5 would cause the universal joint support to be moved horizontally so as to hold the mirror supporting arms at any desired distance away from the wall.

The advantages of my improved device for the purposes intended are too obvious to require special mention. It will be noted that the main extensible supports and the extensible mirror supporting arms balanced upon a universal joint, afford facilities for unlimited adjustment while in use and enable the parts to be compactly folded when not in use.

Having thus described my invention, I claim:

1. An adjustable mirror support, comprising in combination, a base, a tripod form of support having jointed outwardly folding legs, the lower ends of which are jointedly attached to said base and the upper ends to a common connecting member having a vertical axis, a laterally extended supporting member pivotally connected upon a horizontal axis to said common connecting member, mirror supporting means pivotally mounted upon said laterally ex-

tended supporting member, the axes of the two having a rectangular relation to each other, and mirrors mounted upon said mirror supporting means.

2. An adjustable mirror support, comprising, in combination, a base, a tripod form of support having jointed, outwardly folding legs, the lower ends of which are jointedly attached to said base and the upper ends to a common connecting member having a vertical axis, a laterally extended supporting member pivotally connected upon a horizontal axis to said common connecting member, extensible mirror supporting arms pivotally mounted between their ends upon said laterally extended supporting member, the axes of the pivots for supporting said laterally extended member, and said arms respectively having a rectangular relation to each other and mirrors mounted upon said extensible arms.

In testimony whereof, I have signed this specification in the presence of two subscribing witnesses, this 29th day of October, 1914.

SAMUEL SINKLER.
